RODNEY L. SMITH, OF WOLCOTTVILLE, CONNECTICUT.

Letters Patent No. 71,653, dated December 3, 1867.

IMPROVED TWINE-HOLDER.

The Schedule referred to in these Letters Patent and making part of the same.

TO ALL WHOM IT MAY CONCERN:

Be it known that I, RODNEY L. SMITH, of Wolcottville, in the county of Litchfield, and State of Connecticut, have invented, made, and applied to use a certain new and useful Improvement in Twine-Holders; and I do hereby declare the following to be a full, clear, and exact description of the said invention, reference being had to the annexed drawing, making part of this specification, wherein—

Figure 1 is a vertical section of said twine-holder, and

Figure 2 is a plan of the holder as opened, showing the two halves thereof.

Similar marks of reference denote the same parts.

Twine-holders have heretofore been made with a hole at the top for the thread, twine, or cord to be drawn out, and also with a hole at the bottom. In these cases the twine often unwinds, the weight of the hanging end pulling the twine out from the interior of the ball. To avoid this difficulty, a brake has been applied below the holder for the cord to run through, and thereby the required friction has been obtained. In this instance, the brake hanging below the twine-holder is liable to be injured, and is in the way of opening the holder when resting on a table for introducing the ball of twine previous to the holder being hung up.

The nature of my said invention consists in a twine-holder in which a loop or ring is provided at or near the top of the holder, and within the same, over which the cord or twine is led and passed down outside the ball and out through a hole near the centre of the case at the bottom; thereby the weight of the ball of twine becomes a friction to detain the twine as it is drawn out, and to allow a sufficient length to hang down for convenience of use, without the weight of the twine causing it to unwind.

In the drawing, *a* and *b* are the half globular sheet-metal shells of the twine-holder hinged together at *c*, and provided with a catch or lock-pin, *d*, to hold the case together when closed. *e* is a ring by which the twine-holder is to be suspended from a hook, or in any other convenient manner. *f* is a loop or ring attached within the shell *a* at the upper part, and over this the twine is led from the ball, shown by blue lines, thence within the shells *a* and *b*, and out at the hole *i*.

It will now be seen that the ball of twine, resting upon the said twine as it passes out, produces the friction necessary to detain it, as aforesaid.

What I claim, and desire to secure by Letters Patent, is—

The loop or ring within the upper part of the twine-holder, for the purposes and as specified.

In witness whereof, I have hereunto set my signature, this 24th day of October, A. D. 1867.

RODNEY L. SMITH.
